APPARATUS FOR SEALING CARTONS

Harry S. Fox and Kenneth W. Emerson, Honolulu, Territory of Hawaii, assignors to Hawaiian Pineapple Company, Limited, Honolulu, Territory of Hawaii, a corporation of the Territory of Hawaii

Application August 1, 1939, Serial No. 287,776

26 Claims. (Cl. 93—6)

The present invention relates to the closing and sealing of cartons after they have been packed with articles, and more particularly to apparatus for inserting and securing filler strips between the opposed ends of the narrow unmeeting flaps of a packed carton.

The conventional fibreboard carton employed for packing canned goods and the like is rectangular in shape having side and end hinged flaps forming the top and bottom. The combined width of the side flaps is substantially equal to the width of the carton but to make the combined length of the end flaps equal to the length of the carton would involve heavy waste of material in cutting the carton blank, so that, for reasons of economy, these flaps are made shorter than the length of the carton and leave a considerable gap between their ends when closed. The result is an uneven surface at top and bottom of the carton, usually the inner surface, as the side flaps are generally sealed over the end flaps for reasons of appearance and because the spaced end flaps would be apt to catch and tear open during shipment if on the outside of the carton.

This uneven inner surface at top and bottom of the packed cartons is a cause of considerable damage to the contents during shipment, particularly in the case of such articles as canned goods, bottles and the like. In the case of canned goods, for example, the cans in the vertical central layers are, due to the gap at the bottom of the carton, offset below adjacent layers and are capable of greater vertical shifting because of the increased depth of the carton at the central gaps. As a result, the cans in these layers are liable to interlock their end rims or chines, and dent each other and scuff their labels when the carton is subjected to rough handling. For similar reasons, like damage and even breakage is apt to result with bottles and other fragile containers.

To remedy this difficulty, it has heretofore been proposed to provide the carton blank, prior to folding, with tabs secured to a surface at the portions intended to constitute the inner surface of the side flaps, in position to lie within the gaps between the end flaps when the carton is folded. While cartons formed from such blanks are generally satisfactory as regards a smooth inner surface at top and bottom for level riding of the contents, the expense of securing the tabs properly to the blanks is great, requiring special treatment and a time-consuming hand operation or complicated expensive machinery so that the cost of the blank is increased substantially more

than the cost of the tab material added. A further substantial disadvantage of this method is that the thickness of the blanks is doubled so that the space required for shipment and storage is likewise doubled.

It is an object of the present invention to provide apparatus for automatically securing a filler strip in the gap between a pair of end flaps of a carton after it has been formed from the flat blank and packed, thereby obviating the difficulties consequent on the presence of said gap in prior packed cartons while at the same time avoiding any substantial increase in shipping and storage space required for the component parts of the carton. A further object of the invention is to supply filler strip inserting mechanism of relatively inexpensive construction which is adapted to insert the strip in the carton while it is being operated upon by a sealing machine and to make use of means present in such machines for opening up the side flaps and subsequently sealing them to the end flaps so that insertion of the filler strip need not increase the time nor to any significant extent the expense now required for the sealing of cases.

The apparatus of this invention is adapted to insert the filler piece downwardly into the gap between the upper pair of end flaps of a packed carton, said gap being exposed upwardly by opening the upper side flaps. Consequently it can, at a single operation, apply a filler between but one pair of the end flaps, which may be either the top or bottom pair depending upon whether the case is fed thereto right side up or upside down, although, of course, when a filler strip has been secured between one pair of end flaps the position of the case may be reversed and a second filler piece secured between the other pair of end flaps either by the same machine or a successive machine. However, carton sealing machines are generally designed to seal both the top and bottom of the carton in one operation without reversing the position of the case and, consequently, for economic reasons, we prefer to employ the apparatus of the invention in conjunction with apparatus adapted to simultaneously secure a filler piece between the under pair of end flaps, such as that disclosed in co-pending application of Francis N. Todd and Kenneth W. Emerson, Ser. No. 287,783.

With the foregoing and other objects and advantages in mind, the apparatus of the invention will now be more particularly described in conjunction with the appended drawings wherein:

Fig. 1 is a top plan view of part of a carton

sealing machine embodying filler strip inserting mechanism of the invention;

Fig. 2 is a side elevation of the filler tab magazine and ejector mechanism of the invention and of a packed carton thereunder at the start of its actuating engagement with the ejector mechanism, part of the carton being broken away;

Fig. 3 is a side elevation with parts broken away of the magazine and ejector mechanism and of a packed carton thereunder at the end of its actuating engagement with the ejector mechanism, showing the ejected filler piece in position between the end flaps;

Fig. 4 is a plan view of the ejector mechanism taken on a horizontal section through the lower end of the magazine;

Fig. 5 is a front elevation of the magazine and ejector mechanism and of a carton in the position of Fig. 2.

For the complete accomplishment of its purpose, the invention contemplates the provision of means for opening the top side flaps of a packed carton, means for inserting a filler strip into the gap between the top end flaps onto the contents of the carton, and means to then close and seal the top side flaps over the end flaps and filler strip. Suitable flap opening, closing and sealing means are, however, present in carton sealing machines now in use, so that the invention may be considered as in the nature of a modification of such machines by the addition thereto of mechanism for inserting the filler strips at a suitable time during the operation of the machines, and it is so illustrated herein.

In the carton sealing machine shown in Fig. 1, an elongated main frame structure 100 supports a central slide 101 along which the packed cartons A are continuously conveyed from left to right in Fig. 1, between laterally adjustable guide rails 102 by means of propeller bars 103 secured at their ends to endless sprocket chains 104 extending along opposite sides of the slide over driven sprocket wheels 105 at the rear end of the slide and idler sprocket wheels (not shown) at the forward end of the slide. The cartons are advanced along the slide 101 into the path of a pair of front plows 106, suspended from a cross shaft 107 at opposite sides of the slide 101, which enter under the top side flaps, as indicated in Fig. 1, and open them upwardly and outwardly onto horizontal slides 108 secured to the guide rails 102 along opposite sides of the slide 101. As the cartons are advanced beyond the front plows 106 the top side flaps are carried along the slides 108 under a pair of gluing rollers 109 mounted on a cross shaft 110 and fed by glue tanks 111, said rollers 109 applying a coating of glue to the inner face of the top side flaps. As the cartons are further advanced along the slide 101, the top side flaps encounter a pair of rear plows 112 connected to the guide rails 102 at opposite sides of the conveyor, the rear plows acting to fold the top side flaps back over the top end flaps. The cartons then pass under a presser foot 113, suspended over the rear end of the slide 101, which, together with flanged rollers 114 on the rear end of the guide rails 102, press the top side flaps down on to the end flaps sufficiently to effect preliminary sealing of the top of the cartons. The cartons then pass off the rear end of the slide 101 and may enter further apparatus (not shown) which applies final sealing pressure.

A motor 115 is provided at the rear end of

the machine to operate, through suitable drive connections partially indicated in the drawings, driven parts such as the sprockets 105 and the gluing roller shaft 109. The position of the guide rails 102 and of the plows and gluing means associated with them may be adjusted to accommodate different sized cartons by means of the hand shafts 107 and 116, the latter shaft having sprocket and chain connection (not shown) within a casing 117 with a cross shaft 118 through which adjustment of the rear ends of the guide rails 102 and the rear plows 112 is effected. To prevent undesirable springing up of the end flaps while the side flaps are held open, a flat rail 119, indicated by dotted lines in Fig. 1, may be suspended from the casing 116 in position to slidably engage the top surface of the end flaps.

Generally, carton sealing machines such as that illustrated herein are provided with means for simultaneously sealing the top and bottom side flaps of the carton. However, as the present invention is not concerned with means for sealing the bottom of the carton, it has been deemed unnecessary to show or describe them herein.

The case sealing apparatus so far described is substantially similar to that shown and described in United States Patent No. 2,095,258, dated October 12, 1937, to which reference may be had, said patent also describing suitable mechanism for feeding the cartons onto the slide 101 in front of successive pusher bars 104 and means for sealing the bottom of the cartons as they are advanced along the slide.

According to the present invention there is attached to the apparatus so far described means for inserting a filler strip in the gap between the upper end flaps of a carton while it is advancing along the slide 101 with its top side flaps held open. The means for this purpose shown in the accompanying drawings comprises a magazine 10 for a supply of filler strips 11, attached to a suitable support, such as the shaft 107, to overlie the slide 101 between the front plows 106 and rear plows 112, and mechanism, designated generally by the reference numeral 12, adapted to release the bottom filler strip from the magazine to fall into the exposed gap between the upper end flaps of a carton as it is advanced thereunder along the slide 101.

As is more particularly shown in Figs. 2 and 3, the magazine 10 comprises a front wall 13, a rear wall 14 and side walls 15 secured together and to a base plate 16 to form a rectangular box. A bracket arm 17 bolted to the walls 13, 14 serves to secure the magazine in upright position to the supporting structure, centered over the slide 101. The filler strips 11 are stacked flat in the magazine with their ends adjacent the side walls 15, said walls being provided with apertures 18 extending from the top to adjacent the base which show at a glance the condition of the supply of filler strips in the magazine as an indicator for refilling. The magazine is made adjustable for different widths of filler strips by means of vertically disposed guide plates 19 secured to bolts 20 projecting through openings in the front wall 13, the plates bearing against one side edge of the filler strips and being adjustable to and from the rear wall 14 by means of wing nuts 21 on the outer ends of the bolts 20.

The front and rear walls 13 and 14 extend laterally beyond the side walls 15 and are cut away at their lower edges, between the side walls 15, to provide transverse slots 22 and 23. The base plate 16 extends forwardly of the front wall 75

13 and has an upturned forward end 24, the plate being adapted to act as a skid or plow to engage end flaps of the carton that may spring up on opening of the side flaps and press them down close to the contents. The rear edge of the plate 16 is cut away between the side walls 15 to provide a transverse slot 25 coinciding with the slot 23 in the rear wall 14. The upper surface of this plate between the side walls 15 and front wall 13 is provided with longitudinal corrugations 26 (see Fig. 5) which reduce chafage of the filler strips slid thereover.

The lower side edges of the front wall 13 and rear wall 14, beyond the side walls 15, are provided with aligned apertures 27 and 28, connected by a sleeve 29, through which are slidably received rods 30, the forward ends of which are attached, by means of clamps 31 to ejector plate 32. Ejector plate 32 has a thickness less than the depth of the slot 22 and of a filler piece 11, and, as best shown in Figs. 3 and 4, has a rearward end of reduced width corresponding to the width of the slot 22 through which it is adapted to reciprocate on reciprocation of the rods 30, the reduced portion having a length slightly greater than the distance from the front wall 13 to the forward edge of the slot 25 in the base plate 16. A collar 33, adjustably mounted on the rods 30 beyond the rearward end of the plate 32, is adapted to engage the rear wall 14 to limit forward movement of the rods 30 through the apertures 27 and 28 and sleeves 29.

At the rearward ends of the rods 30 there are secured forked members 34 constituting an extension of the rods 30. At the rearward end of each of these forked members, between the side arms thereof, there is pivotally mounted, by means of a stud 35 a trigger plate 36. As shown in Fig. 3, the upper end of each plate 36 above the fork 34, is rounded and provided with a forwardly faced ratchet tooth 37 adapted for engagement with the end of a trigger lever 38 pivotally mounted on a stud 39 between the side arms of each forked member 34 adjacent the forward end thereof. The forward edge of the plate 36 below the fork 34 is provided with a laterally projecting flange 40 (see Fig. 5) adapted to engage the front end of a carton advancing along the slide 101.

50 The forward ends of levers 38 are provided with upwardly extending arms 41 adapted to engage stops 42 adjustably mounted on the rearward ends of threaded rods 43 extending through the outer ends of the front and rear walls 13 and 14 of the magazine, above and parallel to the rods 30. An inverted channel member or hood 44 surrounds the rearward end of each of the levers 38, this hood being adapted to receive the upper end of the trigger plate 36 between its side walls to guide the rear end of the lever 38 into engagement with the tooth 37. Coil springs 45, connected at one end to the collars 33 and at the other end to collars 46 adjustably mounted on the forward end of rods 43, tend to hold the rods 30 and connected parts in their retracted or forward position shown in Fig. 2.

As the carton A is advanced along the slide 101 from the position of Fig. 1 to the position of Fig. 2, its top side flaps S are opened by the front plows 106 fully exposing the top end flaps E which normally lie flat on the upper surface of the contents of the carton, such as the cans C, as shown in Fig. 2. In case the flaps E tend to spring up from that position, they are held down by engagement with the skid-like forward por-

tion of the bottom plate 16 of the magazine. As the carton enters under the magazine, the ejector mechanism is in the position shown in Fig. 2 with the bars 38 and ejector plate 32 in retracted or forward position and with the levers 38 engaging the teeth 37 of the trigger plates 36 to hold the flanges 40 vertically in the path of the advancing carton. When the carton reaches the position of Fig. 2 in which the gap G between the end flaps is approximately centered below the magazine, the front end of the case engages the flanges 40 on the trigger plates 36 as shown in Figs. 2 and 5. As the carton is further advanced to the right of the position shown in Fig. 2, the trigger plates 36 are prevented from turning about their pivots 35 by engagement of the end of the levers 38 with the teeth 37 and consequently these plates and levers, the forks 34, bars 30 and ejector plate 32 are drawn rearwardly with the carton, the rear edge of the ejector plate 32 engaging the forward side edge of the bottom filler strip 11 of the stock in the magazine and pushing it rearwardly in time with the travel of the carton, expelling it sidewise from the magazine through the communicating slots 23 and 25, as indicated in Fig. 4, into the position of Fig. 3, whence it drops flat onto the top of the contents of the carton in the gap G which has remained centered below it.

As the ejection of the filler piece 11 from the magazine is completed, the upwardly projecting arms 41 strike the stops 42 and further forward motion of the carton therefore turns the levers 38 about their pivots 39, releasing them from engagement with the teeth 37 of the trigger plates 36, as shown in Fig. 3. The plates 36 are then free to turn about their pivots to release the slideable parts of the ejector mechanism from operative connection with the carton, these parts being then drawn back over the advancing carton to initial position by the springs 45. The plate 32 is thus withdrawn from under the stack of filler strips, permitting the lowermost strip to drop to position for ejection by the next advancement of the plate 32. As the arms 41 are withdrawn from the stops 42, the rearward ends of the levers 42 fall down upon the rounded upper portion of the plates 36 beyond the teeth 37, these plates being now turned to substantially horizontal position and riding along the top of the carton. As the rear end of the carton advances from under the trigger plates 36, they turn downwardly about their pivots until, under the guidance of hoods 44, the ends of the levers 38 drop to position in front of the teeth 37 and the mechanism is again set in the manner shown in Fig. 2 for repetition of the cycle just described on arrival of the next succeeding carton.

As the carton A with the inserted filler piece advances to the rear end of the machine, the filler piece is held loosely in the gap by the contents C of the carton on which it rests and by the end flaps E which engage its sides if it slides laterally from the position of Fig. 3 during this interval. On reaching the rear plows 112, the top side flaps, 55 which have meanwhile received a coating of adhesive on their inner surface, are refolded over the end flaps and are then sealed thereto by the presser foot 113 and subsequent pressure mechanism. Obviously, if the filler strip 11 is of the same thickness as the end flaps E and the side flaps are coated with adhesive throughout their length, the side flaps will be also simultaneously sealed to the filler strip, although this is not essential, as the mere sealing of the side flaps to 75

the end flaps is sufficient to secure the filler piece permanently, though loosely, in the gap G, it being largely immaterial whether the filler piece is fixed or loose in the gap of the sealed carton.

5. It will be understood that the invention is not limited to the particular type of carton sealing apparatus chosen for the sake of illustrating the invention. Indeed, while it is generally preferable, in accordance with the invention, to insert 10 the filler piece while the carton is being operated on by a sealing machine, and therefore to add the filler inserting mechanism to the sealing machine, it is not essential to do so. For example, the filler inserting mechanism, together with suitable 15 side flap opening means such as the plows 106, may, if desired, be disposed over the conveyer system which carries the packed cartons to the sealing machine, so that the carton reaches the sealing machine with the filler piece already in 20 position in the gap G.

It will also be understood that the invention is not limited to the specific form and arrangement of parts in the filler inserting mechanism but that various changes may be made therein without deviating 25 from the spirit and scope of the invention.

We claim:

1. In apparatus for sealing packed cartons by securing outer flaps over unmeeting inner flaps, the combination of means for opening a pair of 30 said outer flaps to expose the gap between a pair of said unmeeting inner flaps, and to position a filler strip on the contents of said carton between the edges of said exposed gap.

2. In apparatus for sealing packed cartons by 35 securing outer flaps over unmeeting inner flaps, the combination of means for opening a pair of said outer flaps to expose the gap between a pair of said unmeeting inner flaps, means to position a filler strip on the contents of said carton between the edges of said exposed gap, means to apply adhesive to the inner surface of said outer flaps, and means to close said outer flaps over said inner flaps and filler strip.

3. In apparatus for sealing packed cartons by 45 securing outer flaps over unmeeting inner flaps, means for advancing a packed carton with a pair of said outer flaps open to expose the gap between a pair of said unmeeting inner flaps and means to position a filler strip on the contents of said carton between the edges of said exposed gap.

4. In apparatus for sealing packed cartons by securing outer flaps over unmeeting inner flaps, means for advancing a packed carton with a pair of said outer flaps open to expose the gap between 55 a pair of said unmeeting inner flaps, means to position a filler strip on the contents of the carton between the edges of said exposed gap, means to apply adhesive to the inner surface of said outer flaps, and means to close said outer flaps over said inner flaps and filler strip.

5. In apparatus for sealing packed cartons by securing outer flaps over unmeeting inner flaps, means for opening the outer flaps at the top of the carton to expose the gap between the top inner flaps and means to drop a filler strip to lie in horizontal position in said exposed gap.

6. In apparatus for sealing packed cartons by securing outer flaps over unmeeting inner flaps, means for opening the outer flaps at the top of 70 the carton to expose the gap between the top inner flaps, means to drop a filler strip to lie in horizontal position in said exposed gap, means to apply adhesive to the inner surface of said outer flaps, and means to close said outer flaps over said 75 inner flaps and filler strip.

7. In apparatus for sealing packed cartons by securing together pairs of side and end flaps in overlapped relation, the combination of means to feed a packed carton with an unmeeting pair of said flaps exposed at the top in substantially horizontal position, means to drop a filler strip to horizontal position in the gap between the ends of said exposed unmeeting flaps and means to secure said overlapping flaps to said filler strip lying in said gap. 10

8. In apparatus for sealing packed cartons by securing outer flaps over unmeeting inner flaps, means for advancing a packed carton with the outer flaps at the top of the carton open to expose the top inner flaps and means to drop a filler strip 15 to horizontal position in the gap between said exposed inner flaps.

9. In apparatus for sealing packed cartons by securing outer flaps over unmeeting inner flaps, means for advancing a packed carton with the outer flaps at the top of the carton open to expose the top inner flaps, means to drop a filler strip to horizontal position in the gap between said exposed inner flaps, means to apply adhesive to the inner surface of said open outer flaps and means 25 to close said outer flaps over said inner flaps and filler strip.

10. In apparatus of the character described, means for advancing a packed carton having at the top thereof unmeeting inner flaps and outer flaps adapted to be sealed thereover, means for opening said outer flaps to fully expose the gap between said inner flaps and means to drop a filler strip to horizontal position in said exposed gap. 30

11. In apparatus of the character described, means for advancing a packed carton having at the top thereof unmeeting inner flaps and outer flaps adapted to be sealed thereover, means for opening said outer flaps to fully expose the gap between said inner flaps, means to apply adhesive 40 to the inner surface of said outer flaps, means to drop a filler strip into said gap, and means to close said outer flaps over said inner flaps and filler strip.

12. In apparatus of the character described, means for advancing a packed carton having at the top thereof unmeeting inner flaps and outer flaps adapted to be sealed thereover, means for opening said outer flaps to fully expose the gap between said inner flaps, means to apply adhesive 50 to the inner surface of said outer flaps, means to drop a filler strip into said gap, means to close said outer flaps over said inner flaps and filler strip and means to prevent said unmeeting flaps from rising substantially off the contents of the 55 packed carton.

13. Apparatus for inserting a filler strip in the gap between the ends of unmeeting flaps in a packed carton, comprising a conveyer adapted to advance a packed carton with said unmeeting flaps exposed, means for supporting a filler strip over the path of travel of the carton on said conveyer, and means operated in timed relation to the travel of the carton on the conveyer to 60 release said filler strip from said supporting means when in registration with said gap.

14. Apparatus for inserting a filler strip in the gap between the ends of unmeeting flaps in a packed carton, comprising a conveyer adapted to 70 advance a packed carton with said unmeeting flaps exposed, means for supporting a filler strip over the path of travel of the carton on said conveyer, and means operated by the advancing carton to release said filler strip from said sup- 75

porting means when in registration with said gap.

15. Apparatus for inserting a filler strip in the gap between the ends of unmeeting flaps in a packed carton, comprising a conveyer adapted to advance a packed carton with said unmeeting flaps exposed at the top thereof, means for positioning a filler strip over the path of travel of the carton on said conveyer, and means operative on arrival of the carton under said positioning means to release said filler strip to drop to horizontal position in said gap.

16. Apparatus for inserting a filler strip in the gap between the ends of unmeeting flaps in a packed carton, comprising a conveyer adapted to advance a packed carton with said unmeeting flaps exposed at the top thereof, means for positioning a filler strip over the path of travel of the carton on said conveyer, and means operated by the advancing carton to release said filler strip to drop to horizontal position in said gap.

17. Apparatus for inserting a filler strip in the gap between the ends of unmeeting flaps in a packed carton, comprising a conveyer adapted to advance a packed carton with said unmeeting flaps exposed, a magazine for storing a supply of filler strips adjacent the path of travel of the carton on the conveyer, means to eject a filler strip from said magazine over the path of travel of the carton on said conveyer, and means operating said ejecting means in timed relation to the travel of the carton on the conveyer whereby said filler strip is ejected in registration with said gap.

18. Apparatus for inserting a filler strip in the gap between the ends of unmeeting flaps in a packed carton, comprising a conveyer adapted to advance a packed carton with said unmeeting flaps exposed, a magazine for storing a supply of filler strips adjacent the path of travel of the carton on the conveyer, means to eject a filler strip from said magazine over the path of travel of the carton on said conveyer, and means engageable with the advancing carton to operate said ejector means to eject said filler strip in registration with said gap.

19. Apparatus for inserting a filler strip in the gap between the ends of unmeeting flaps in a packed carton, comprising a conveyer adapted to advance a packed carton with said unmeeting flaps exposed at the top thereof, a magazine for storing a supply of filler strips to one side of the path of travel of the carton on the conveyer, means to eject a filler strip from said magazine over the path of travel of the carton on said conveyer, and means operating said ejecting means in timed relation to the travel of the carton on the conveyer whereby said ejected filler strip drops to horizontal position in said gap.

20. Apparatus for inserting a filler strip in the gap between the ends of unmeeting flaps in a packed carton, comprising a conveyer adapted to advance a packed carton with said unmeeting flaps exposed at the top thereof, a magazine for storing a stack of filler strips over the path of travel of the carton on the conveyer, and means operative on arrival of the carton under said magazine to release a filler strip therefrom in position to drop to horizontal position in said gap.

21. Apparatus for inserting a filler strip in the gap between the ends of unmeeting flaps in a packed carton, comprising a conveyer adapted to advance a packed carton with said unmeeting

flaps exposed at the top thereof, a magazine for storing a stack of filler strips over the path of travel of the carton on the conveyer and means operated by the advancing carton to release a filler strip from the magazine in position to drop to horizontal position in said gap.

22. Apparatus for inserting a filler strip in the gap between the ends of unmeeting flaps in a packed carton, comprising a conveyer adapted to advance a packed carton with said unmeeting flaps exposed at the top thereof, means to register a filler strip above said gap in said carton advancing along said conveyer, and means to release said filler strip while in registry with said gap whereby said strip drops into said gap to lie horizontally on the contents of said carton.

23. Apparatus for inserting a filler strip in the gap between the ends of unmeeting flaps in a packed carton, comprising a conveyer adapted to advance a packed carton with said unmeeting flaps exposed at the top thereof, means to register a filler strip above said gap in said carton advancing along said conveyer, and means operated by the advancing carton to release said filler strip while in registry with said gap whereby said strip drops into said gap to lie horizontally on the contents of said carton.

24. Apparatus for inserting a filler strip in the gap between the ends of unmeeting flaps in a carton, comprising a conveyer adapted to advance a carton with said unmeeting flaps exposed at the top thereof, a magazine for a stack of filler strips disposed adjacent the path of said advancing carton, a slot in a side wall of the magazine affording passage for a filler strip of said stack laterally therethrough, ejector means engageable with said filler strip to force it through said slot, and means engageable with a carton advancing on the conveyer to operate said ejector means to eject said filler strip from said magazine over said advancing carton in registration with said gap.

25. Apparatus for inserting a filler strip in the gap between the ends of unmeeting flaps in a carton, comprising a conveyer adapted to advance a carton with said unmeeting flaps exposed at the top thereof, a magazine for a stack of filler strips disposed adjacent the path of said advancing carton, a slot in a side wall of the magazine affording passage for a filler strip of said stack laterally therethrough, a reciprocal slide adjacent the magazine and adapted to engage said filler strip to force it through said slot, and trigger means connected to said slide and engageable with said advancing carton to operate said slide to eject said strip in registration with said gap.

26. Apparatus for inserting a filler strip in the gap between the ends of unmeeting flaps in a carton, comprising a conveyer adapted to advance a carton with said unmeeting flaps exposed at the top thereof, a magazine for a stack of filler strips disposed adjacent the path of said advancing carton, a slot in a side wall of the magazine affording passage for a filler strip of said stack laterally therethrough, reciprocal pusher means adjacent the magazine and adapted to engage said filler strip to force it through said slot, means engageable with said advancing carton to operate said pusher means to eject said filler strip in registration with said gap, and means to return said pusher means to initial position.

CERTIFICATE OF CORRECTION.

Patent No. 2,203,900.

June 11, 1940.

HARRY S. FOX, ET AL.

It is hereby certified that error appears in the printed specification of the above numbered patent requiring correction as follows: Page 4, first column, line 31, claim 1, after the word "and" insert --means--; and that the said Letters Patent should be read with this correction therein that the same may conform to the record of the case in the Patent Office.

Signed and sealed this 23rd day of July, A. D. 1940.

(Seal)

Henry Van Arsdale,
Acting Commissioner of Patents.
